UNITED STATES PATENT OFFICE.

LOUIS J. JOHNSON, OF ELK FALLS, KANSAS.

CAR-COUPLING.

SPECIFICATION forming part of Letters Patent No. 227,538, dated May 11, 1880.

Application filed February 27, 1880.

To all whom it may concern:

Be it known that I, LOUIS J. JOHNSON, of Elk Falls, in the county of Elk and State of Kansas, have invented a new and valuable 5 Improvement in Car-Couplings; and I do hereby declare that the following is a full, clear, and exact description of the construction and operation of the same, reference being had to the annexed drawings, making a 10 part of this specification, and to the letters and figures of reference marked thereon.

Figure 1 of the drawings is a representation of a rear-end view of my improved car-coupling. Fig. 2 is a longitudinal vertical section 15 thereof. Fig. 3 is a bottom view of the same, partly in section; and Fig. 4 is a detail view of the coupling-bar.

This invention has for its object to provide a durable and efficient car-coupling which can 20 be readily operated without involving the necessity of going in between the approaching ends of the cars to arrange the coupling devices.

The invention consists in the construction 25 and novel arrangement of upper and lower sections or jaws pivoted together, forming a draw-bar, lateral bearing-boxes containing springs in which the journals of the draw-bar are seated, a coupling-bar having a head connected to 30 the shank by a beveled shoulder, and lever devices for keeping the jaws closed upon the head of the coupling-bar, all as hereinafter fully shown and described.

In the accompanying drawings, the letter A 35 designates the bottom of the car or framework to which the draw-bar is connected. This draw-bar is composed of an upper section, B, and a lower section, C, each of which extends its entire length, and which are pivoted to 40 together near their middle portions, as indicated at *a*, as shown in Fig. 2. Usually these sections are pivoted together by a strong transverse rod or bar, *b*, which passes through the stout side walls, *c*, of the sections, and extends into 45 the lateral bearing-boxes D D, which are bolted to the bottom of the car on each side of the draw-bar. These boxes contain springs, against which the ends of the journals *b* abut, and by which said journals are cushioned and 50 the draw-bar protected from injury by the violent shocks to which it is subjected. The in-

ner walls of these boxes D D are slotted for the journal-bearings, so as to afford sufficient play, and at the same time to locate the draw-bar a little below the car-bottom, so that it will 55 have some play upon its journals and be capable of an inclination downward or upward, according to the varying heights of the cars to which it may be connected. In this manner the draft will be in a direct line between the journals of the draw-bars, and there will be no strain on the coupling-bar to bend or break it or to cause leverage which might open the jaws of the draw-head B and C. These jaws are kept open at their front or mouth ends by 60 means of a spring, E, arranged between them in suitable seats, and the mouth being bell-shaped the rounded and beveled head of the coupling-bar F readily enters for engagement. This is effected when the head *e* enters the recess or throat *g*, behind the shoulders *h* of the sections, said shoulders being notched at *k* to embrace the shank *l* of the coupling-bar when these shoulders or lips are brought together. This is accomplished by forcing apart the rear 70 ends of the draw-bar sections by means of an arrangement of levers, a toggle-joint device, H, being usually employed, its ends being attached to the rear ends of the jaw-sections and its middle or jointed portion operated by means 75 of a transverse lever, K, connected at one end to an arm, *n*, extending to the rear of the draw-bar, and on the other to a chain, *s*, extending forward, and a winding-post, L, extending downward through the car-platform, to which 80 the forward end of said chain is connected, and by which said lever is operated to open and close the jaws B C. This winding-post is designed to be supplied with a ratchet-and-pawl stop, to hold it to position when the chain 85 is wound sufficiently to close the jaws of the draw-bar.

The shoulder *z* of the head of the coupling-bar is made beveled, as indicated in the drawings, so that when the jaws are opened by the 90 action of the spring between them, after the chain is loosened, the coupling-bar will at once become disconnected, the head slipping easily from its bearing-recess *g*. The coupling is therefore effected by the clutch of the 95 jaws B and C on the head of the bar, and its shank is also forcibly grasped by the notches 100

k of the lips or shoulders *h*, so that it is held with sufficient rigidity to enter the mouth of an opposite-approaching draw-head.

For use in connecting with draw-heads arranged for the common link and pin, coupling-bars may be made with a head at one end and a loop or eye at the other.

Having described this invention, what I claim, and desire to secure by Letters Patent, is—

1. The draw-head consisting of the upper and lower sections, B C, pivoted together, the opening-spring E, the side bearing-boxes, D, having springs against which the journals *b* of the draw-head abut, and suitable lever mech-

anism for closing the section-jaws, substantially as specified.

2. The combination, with the pivoted upper and lower sections, B C, and the opening-spring E between the two, of the rear toggle-joint, H, the transverse operating lever K, and the operating-chain *s*, substantially as specified.

In testimony that I claim the above I have hereunto subscribed my name in the presence of two witnesses.

LOUIS J. JOHNSON.

Witnesses:

JOHN RANSOM,
JOE CARR.
